Patented Oct. 4, 1910.

UNITED STATES PATENT OFFICE.

FRED HERBERT, OF COSHOCOTON, OHIO.

APPARATUS FOR USE IN CASTING PIPES.

972,107.

Specification of Letters Patent.

Patented Oct. 4, 1910.

Application filed July 14, 1909. Serial No. 507,487.

To all whom it may concern:

Be it known that I, FRED HERBERT, a subject of the King of Great Britain, at present residing at Coshocton, county of Coshocton, 5 State of Ohio, have made a certain new and useful Invention in Apparatus for Use in Casting Pipes, of which the following is a specification.

The invention relates to apparatus for use 10 in casting pipes or other articles and particularly to means employed in properly assembling the various parts required in the casting operation.

The object of the invention is to provide 15 means whereby the parts required in casting pipe sections may be quickly assembled into assembled relation and in true and perfect relative positions.

A further object is to provide means 20 whereby, in assembling the mold and core preparatory to casting a pipe section, the parts are properly centered and protected against injury.

A further object is to provide means for 25 efficiently venting the apparatus in case of the formation of gases, steam or the like by the molten iron when introduced to the mold.

Other objects of the invention will appear 30 more fully hereinafter.

The invention consists substantially in the 35 construction, combination, location and relative arrangement of parts, all as will be more fully hereinafter set forth, as shown in the accompanying drawing, and finally pointed out in the appended claims.

In the manufacture of iron pipe sections, especially where molds and cores are employed, it is very important to assemble the core and mold in absolutely centered relation, as any deflection or variation from such relation results in the production of a faulty pipe section and a consequent loss of time as well as of material and labor, with the expense incident thereto. Where molded or 45 other suitably shaped pattern heads are employed to properly shape the ends of the pipe section to be cast it is not only important to properly center the head with absolute accuracy in its relation to the mold and the core, but it is also very important to protect the head against the danger of injury by being broken down, crushed, warped or bent by the core striking or pressing thereagainst while being placed in assembled relation. 55 It is equally important and necessary to accurately guide the core into its assembled

relation and to center the same in position in order to insure the production of a perfect casting of the pipe section.

It is among the special purposes of my invention to provide means for accomplishing these and other objects.

In the accompanying drawing I have shown a construction and arrangement for accomplishing my objects and purposes, and 65 wherein—

Figure 1 is a view partly in side elevation and partly in longitudinal section on the line 1, 1, Fig. 2, of a flask showing the relation of the mold, core and head in assembled position with the pipe section cast therein, and embodying the principles of my invention. Fig. 2 is a transverse section on the line 2, 2, Fig. 1. Fig. 3 is a broken view in section on the line 3, 3, Fig. 2, and somewhat enlarged. Figs. 4 and 5, are detail views in transverse section, respectively taken on the lines 4, 4, and 5, 5, Fig. 1.

The same part is designated by the same reference sign wherever it occurs throughout 80 the several views.

The mold within which the pipe section is cast is formed within a flask, which, in the form I have selected to illustrate the principles of my invention, comprises the two parts or halves 6, 7, adapted to be secured together in any suitable or convenient manner, as, for instance, by the cotters and wedges indicated at 8, and which may be provided with suitable means for supporting and handling the same. The mold, indicated at 9, which may be of any suitable or desired material, usually and preferably of sand, is formed within the flask and suitably shaped and rammed therein in any well known, suitable or convenient manner, and given the desired contour of interior surface.

The core 10, may be of any suitable form, shape, construction and material. Ordinarily cores are formed of sand which is applied to the exterior surface of a core bar 11, and suitably shaped or compressed thereon by ramming or otherwise, as may be desired. In assembling the core and mold preparatory to the casting operation the core is inserted longitudinally into the mold so as to form a space between the exterior surface of the core and the interior surface of the mold into which space the molten metal is poured to form the pipe section 12. In order to assemble the parts in truly centered relation, I employ a plate 13, having an upturned

flange 14, adapted to engage over or against a peripheral flange 15, at the end of the flask. The plate 13, may be secured to the flask end when once fitted into place in any suitable 5 or convenient manner, preferably in a manner to be readily detachable therefrom. A convenient means is shown consisting of cotter bolts 16, and pins or wedges 17.

In practice I prefer to machine the interior 10 surface or wall of the flange 14, in accurate concentric relation to the exterior wall or surface of the flange 15 of the flask, so that the plate 13 will not fit or be received on the end of the flask unless the sections of the 15 latter are completely clamped and secured together. In this manner I insure against any irregularity in the formation of the mold due to the flask sections being improperly secured together, since the plate 13, will 20 not fit onto the end of the flask unless the flask sections are properly and completely secured together.

The inner surface of the plate 13, is recessed as at 21 to receive the base 18, of a 25 sand head, the flange or sleeve 19, of said head extending into the interior of the mold. This head may be formed of any suitable material, as, for instance, sand, and its function is to coöperate with the mold and the 30 core to shape the socket end of the pipe section to be cast. To this end it is properly shaped and rammed into form to be received upon the end plate 13, before the latter is applied to the end of the flask in assembling 35 the parts. Since this head plays a most important part in the proper shaping of the socket end of the pipe it is extremely desirable that it be truly centered with absolute accuracy with reference to the mold, and, 40 as well, with reference to the core, and since it must coöperate with the core any possibility of the core striking against, crushing or breaking down the head or any part or portion thereof, or otherwise warping, bending, 45 or injuring the same must be avoided, while at the same time affording ample support both for the core and the portion 19 of the head. To attain these objects, I provide the end plate 13, with a central flange or 50 sleeve 20, which extends inwardly into the flask and forms, on its exterior surface, a backing or support for the sleeve or portion 19 of the head. In order to facilitate the placing of the head on the centering plate 55 13, the central flange or sleeve 20, may be slightly tapered exteriorly, as indicated by the heavy line at 22, Fig. 5.

In order that the core may be properly supported when inserted into the mold without having its weight imposed on the sleeve 19 of the head, I arrange the core to be received, supported and centered on the central flange or sleeve 20, of the centering plate 13. To this end I prefer to bevel off 60 65 the sleeve or flange 20, on the interior of the

inner end thereof, as indicated at 23, and I similarly bevel off the exterior surface of the adjacent end of the core, as shown. In this manner I provided a metal cone socket into which is received the cone shaped end of the core thereby forming a centering support 70 for the cone with reference to the mold as well as the head and without incurring the danger of injuring the head.

In order to secure absolute centering relation of the parts I propose to machine the 75 surfaces of the recess 21, and of the flange or sleeve 20 of the end or centering plate 13, in truly concentric relation with respect to the flanges 14 and 15, and consequently I not 80 only secure an efficient support and backing for the sleeve or portion 19 of the head but I also secure an absolute centering of the several parts when in their assembled relation.

It is important to properly guide the core 85 into its seat in the inner end of the central flange or sleeve 19 and to avoid the danger of the core striking against the inner surface of the mold or otherwise causing injury 90 while the core is being inserted into its assembled position. To this end I provide the core bar 11, with an extended end 25, adapted to pass through a centered bore 26, of the centering plate with sufficient loose- 95 ness of fit to enable said end to pass freely through but forming a guide therefor.

If desired and preferably, the centering flange or sleeve 20, and its centering extension having the bore 26, may be formed 100 separate from the plate 13, and fitted thereto, as for instance, by providing the centering sleeve or flange with a beveled, and preferably machined surface adapted to be received and to fit the correspondingly shaped 105 and machined seat in the plate 13, as clearly indicated at 80, Fig. 3. By making these parts in separate pieces the work of manufacturing the same is greatly facilitated as is also the handling thereof, especially in 110 the case of large sized molds.

It will also be seen that the lower end 115 surface of the mold 9, meets and bears against the surface of the head 18, on a bevel, as indicated at 81, instead of resting thereon squarely. The advantage of this is that in the arrangement shown I reduce the danger of crushing the mold or head at this point, but more important than this any finn 120 that may be produced at this point in the casting operation by reason of metal being forced into the joint, is more easily and satisfactorily removed when formed at an angle and with less danger of injury to the finished pipe.

In assembling the parts so far described, the flask with its mold, the centering plate, the head pattern and the core having been previously made and finished, the head, is placed in position on the end or centering 125

plate, and the latter is then applied and secured to the end of the flask. The core is then inserted longitudinally through the flask and mold and is received and centered upon the center flange of the centering plate, being guided to its seat by the extension 25, of the core bar operating through the central opening 26 of the end plate.

In order to still further insure the production of a perfect casting of the pipe section it is necessary to accurately center the other end of the core within the mold. This result is accomplished in accordance with my invention, by forming a collar 27, on the core 15 which is designed to bear against the interior surface of the mold at the upper or metal receiving end of the latter. In practice this collar is formed integrally with the core at the time the core is made and by bearing 20 against the interior surface of the mold forms an efficient centering means to hold the core and mold in truly centered relation without resorting to crude or improvised centering expedients which, in practice, are 25 too often inefficient for the purpose. Suitable gates or passages 28, around or through the collar 27 afford means for introducing the molten metal to the assembled apparatus to produce the pipe section casting.

From the foregoing description it will be seen that unless the flask is properly closed the centering plate will not fit onto the ends thereof. It will also be seen that the head pattern is made to rest entirely on machined 35 surfaces so that it is compelled to be perfectly true and absolutely centered.

By machining at one setting the several surfaces of the end plate all the parts concerned in the centering function of said plate 40 are truly and accurately centered. The head pattern is not required to form a seat for or to take the weight of the core, nor to contact therewith and hence is protected against the danger of being injured, crushed or 45 warped thereby. Moreover, since the core is centered upon a machined metal surface it is more accurately and certainly centered, than would be possible if centered upon a molded head pattern. Injury to the core or 50 to the mold is prevented by the provision of the guide for the core while being inserted into the mold. The head patterns can be made separately and hence only a few centering plates are necessary and by slightly tapering the bores of the heads they can be 55 very easily and readily placed in position on the plates.

By forming an integral collar on the upper end of the core I am enabled to secure accurate centering of the core in the upper end of the mold, and the use at this point of separate centering heads is entirely obviated.

In the operation of introducing the molten metal to the apparatus to form the pipe casting, it frequently happens that gases

steam or the like are generated within the inclosed space in which such metal is received. In order to avoid damage or injury resulting from such gases or the like, and to form vents therefor, I provide channels 20 or grooves in the inner surface of the recess 21, of the centering plate 13, in which the base 18 of the head rests, and similar channels or grooves in the interior surface of the central flange or sleeve 20, on which is received the sleeve 19, of the head, and I form ducts or passages 30, through said plate and central sleeve, as clearly shown, through which channels, ducts or passages the generated gases may be readily vented and dispersed.

It is obvious that many variations and changes in the details of construction and arrangement of parts may readily occur to persons skilled in the art and still fall within the spirit and scope of my invention. I do not desire therefore, to be limited or restricted to the exact and specific details shown and described. But

Having now set forth the object and nature of my invention and a construction embodying the principles thereof, and having described such construction, its objects, purposes and mode of operation, what I claim as new and useful and of my own invention, and desire to secure by Letters Patent is:—

1. The combination with a mold flask, of a centering plate having a central sleeve, a core received longitudinally within the flask and having one end extended to be engaged and centered by said sleeve, means carried by the other end of said core to be engaged and centered by the mold in said flask, and means for securing the plate to the end of the flask.

2. The combination with a flask and mold, the latter having a flaring end surface at one end thereof, of a core adapted to be inserted longitudinally into the flask and mold, and having an integral collar thereon at one end to engage within the mold adjacent the flaring end surface thereof to center the parts, and means for automatically centering the other end of the core within the mold by the insertion of the core into the mold.

3. The combination with a flask and mold, the latter having a flaring end surface at one end thereof, the mold having a pouring gate passage formed therein, adjacent its flaring end, of a core adapted to be inserted longitudinally into the flask and mold, and having an integral collar to engage within the mold adjacent the flaring end surface thereof to center the parts, and means for automatically centering the other end of the core within the mold by the insertion of the core into the mold.

4. The combination with a mold flask, of

- an end plate having a central seat, and the flange to encompass the end of the flask, said plate having bent openings therethrough and a recess and a central sleeve, a pattern sand head fitted over said sleeve and received in said seat, a core seated in the end of said sleeve, the flange, recess, sleeve and seat of said plate being machined to true concentric relation.
10. 5. The combination with a mold flask, of a core adapted to be inserted longitudinally into the mold flask, and having an integral collar at one end to engage the mold and center the parts and means for automatically centering the other end of the core when inserted into the flask.
15. 6. The combination with a mold flask, of a core having an integral collar thereon at one end to engage and rest on the mold whereby said parts are centered, means for automatically centering the other end of the core with relation to the flask and mold and gates or passages formed in the mold around said collar.
20. 7. The combination with a mold flask and mold, of a pattern sand head fitted to the end of said flask and mold and abutting against the end of the mold, the meeting surfaces of the mold and head being inclined or beveled.
25. 8. The combination with a mold flask, of a centering plate applied to the end thereof, said plate having a beveled central seat formed therein, and a cylindrical centering sleeve having a correspondingly beveled surface to be received in said seat.
30. 9. The combination with a mold flask, and a centering plate applied to one end thereof, said plate having central opening therethrough, of a core and bar, said bar having one end extended, and carrying a collar at its other end, and adapted to be inserted endwise into said mold flask, the extended end of the bar entering the central opening of the centering plate, and the collar engaging the mold whereby the core and bar automatically center themselves at both ends with reference to the mold flask as they reach their fully inserted positions.
35. 10. In an apparatus for use in making pipe sections, the combination with a mold flask and mold, said mold having a flaring upper end surface, and a pouring gate formed therein, of a core and a collar formed integrally with the core, said core and collar arranged to be inserted into the mold, said collar engaging within the mold adjacent the flaring end surface thereof for centering the core with reference to the mold, whereby the pouring well for the casting is completed by the insertion of the core into the mold.
11. In an apparatus for use in making pipe sections, the combination with a flask and mold, the latter having an integral flaring upper end forming a pouring well, and having a gate passage, of a core arranged to be inserted into the mold, means for centering the core and mold at their lower ends, and a collar formed integrally with the core and engaging the upper end of the mold to center the core, said collar cooperating with the flaring end of the mold to complete the gate.
15. 12. The combination with a mold flask and mold, of a centering plate, a pattern sand head carried thereby and contacting at its peripheral edge with the end of the mold, the meeting surfaces of the mold and pattern head being beveled, and means for detachably securing said plate to the end of the flask.
20. 13. The combination with a mold flask and mold, of a pattern sand head arranged to be inserted into the end of the mold, said pattern head having a flange to abut against the end of the mold, the meeting surfaces of the mold and head being beveled, and means for retaining the head in place.
25. 14. The combination with a mold flask and mold, of a plate having a seat formed therein, a pattern sand head mounted in said seat and having a central sleeve portion extending into the mold, and a flange portion to abut against the end of the mold, the abutting surfaces of the head and mold being beveled, and means for detachably securing the plate to the flask.
30. 15. The combination with a mold flask and mold, of a centering plate having a central sleeve extending into the mold, a pattern sand head having a central cylindrical portion fitting over said sleeve, said sand head having a flange portion to abut against the end of the mold, and means for securing the centering plate to the end of the flask.
35. 16. The combination with a mold flask, of a core adapted to be inserted longitudinally into the mold flask and having an integral collar thereon at one end to engage the mold and center the parts, a gate, and means for automatically centering the other end of the core when inserted into the flask, the gate communicating with the interior of the mold.
40. In testimony whereof I have hereunto set my hand in the presence of the subscribing witnesses, on this 12th day of July, A. D. 1909.
115. FRED HERBERT.
